FLOOD LIGHT OR SIMILAR ARTICLE

Henry R. Hahn, Portland, Conn., assignor to Infranor of North America, Inc., Berlin, Conn., a corporation of Connecticut

Filed Sept. 17, 1964, Ser. No. 81,758

Term of patent 14 years

(Cl. D48—20)

FIG. 1

FIG. 1 is a rear elevational view of a flood light embodying my new design.

FIG. 2 is a perspective view showing the front and one side of the flood light of FIG. 1.

The side of the flood light of FIG. 1 opposite to the side shown in FIG. 2 is similar in appearance to the side shown in FIG. 2.

I claim:

The ornamental design for a flood light or similar article, substantially as shown and described.
